UNITED STATES PATENT OFFICE.

WILLIAM L. HAMILTON, OF BANGOR, MICHIGAN.

DIAPHRAGM FOR PRESSURE-CONTROLLING DEVICES.

Application filed December 5, 1918. Serial No. 342,610.

To all whom it may concern:

Be it known that I, WILLIAM L. HAMILTON, a citizen of the United States, and a resident of Bangor, in the county of Van Buren and State of Michigan, have invented a new and Improved Diaphragm for Pressure-Controlling Devices, of which the following is a full, clear, and exact description.

The object of the invention is to provide a new and improved diaphragm for pressure controlling devices arranged to provide an exceedingly large throw with a view to render the pressure controlling device exceedingly sensitive to readily respond to the variations in the pressure.

Another object is to provide a diaphragm which is exceedingly simple and durable in construction and not liable to get out of order easily.

With these and other objects in view, the invention consists of certain novel features of construction, as hereinafter shown and described and then specifically pointed out in the claims.

A practical embodiment of the invention is represented in the accompanying drawings forming a part of this specification, in which similar characters of reference indicate corresponding parts in all the views.

Figure 1 is a side elevation of the improved diaphragm as applied to an automatic pressure operated switch shown in section, and such, for instance, as illustrated and described in the application for Letters Patent, Serial No. 253,489, filed by me on September 10, 1918;

Figure 2 is a sectional plan view of the same on the line 2—2 of Figure 1; and

Figure 3 is a cross section of the same on the line 3—3 of Figure 1.

The improved diaphragm is shown applied to a pressure operated switch having a support 10, a lever 11 pressed on by a spring 12 and connected by a spring 13 with the movable member 14 of a knife switch mounted on the support 10. The diaphragm shown in Figure 1 comprises a plurality of diaphragm chambers, for instance, two chambers 20 and 21 each formed of an annular member 22 and top and bottom diaphragms 23 and 24 having their curved edges soldered or otherwise secured to the annular member 22. The bottom diaphragm 23 of the lower diaphragm chamber 20 rests on a projection 25 forming part of the support 10, and interposed between

the top diaphragm 23 of the diaphragm chamber 20 and the bottom diaphragm 23 of the diaphragm chamber 21 is interposed a disk 26, and a similar disk 27 rests on the top diaphragm 23 of the diaphragm chamber 21. This disk 27 is engaged by lugs 28 depending from the lever 11 previously mentioned. The lower diaphragm chamber 20 is connected with one end 30 of a flexible tube 31 having its other end 32 engaging a nipple 33 screwed or otherwise fastened to the support 10 and connected with a source of fluid pressure supply such, for instance, as a reservoir containing compressed air or other fluid under pressure pumped into the reservoir by a pump actuated by an electric motor. The flexible tube 31, after leaving the nipple 33 is formed into a coil surrounding the annular member 22 of the diaphragm chamber 20, and the end 30 of the flexible tube is connected with the annular member 22 and opens into the chamber. The other diaphragm member 21 is connected at its annular member 22 with one end 34 of a flexible tube 35 having its other end 36 engaging the nipple 33 so that both flexible tubes 31 and 35 are supplied simultaneously with the same fluid under pressure and hence the four diaphragms of the two diaphragm chambers 20 and 21 are simultaneously actuated, and the aggregate amount of their throw is transmitted to the lever 11 thus rendering the switch exceedingly sensitive.

It is understood that although the diaphragm is shown applied to an automatic pressure operated switch, it is evident that the diaphragm may be used on pressure regulated valves and other pressure controlled devices, and it is also understood that I do not limit myself to the number of diaphragm chambers used, as more such chambers or only a single one may be employed.

It will be noticed that by connecting the flexible tube with the peripheral or annular member 22 of the corresponding diaphragm chamber the action of the top and bottom diaphragms 23 and 24 is not impeded in the least.

By using the diaphragm on an automatic pressure operated switch such, for instance, as shown and described in the application above referred to, the bonnet 40 can now be formed as an integral part of the support 10, instead of being bolted to the support 110 to fasten the usual disk diaphragm in place as shown in said application.

Having thus described my invention, I claim as new and desire to secure by Letters Patent:—

1. A diaphragm for pressure regulators and other devices, comprising a plurality of closed diaphragm chambers and a flexible tube connected with each chamber and connected with a source of pressure supply to subject the diaphragm chambers simultaneously to the same pressure.
  2. A diaphragm for pressure regulators and other devices, comprising a plurality of closed diaphragm chambers each having flexible top and bottom diaphragms, and flexible tubes connected with a source of pressure supply and connected with the said chambers, the latter being adapted to act collectively on the part of the pressure regulator to be actuated.
  3. A diaphragm for pressure regulators and other devices, comprising a plurality of closed chambers, each having a flexible top and a flexible bottom, a solid support for the bottom of one of the said chambers to rest on, a solid member interposed between the chambers, and a solid top member on the top of the other chamber and flexible tubes connected with the said chambers and connected with a source of pressure supply.
  4. A diaphragm for pressure regulators and other devices, comprising a plurality of closed chambers each having a flexible top and a flexible bottom, a solid support for the bottom of one of the said chambers to rest on, a solid member interposed be-
- 40 45 50 55 60 65
- tween the chambers, and a solid top member on the top of the other chamber and adapted to be engaged by the part of the regulator to be actuated, flexible tubes connected at one end with the said chambers and a nipple engaging the other ends of the said tubes and adapted to connect with a source of pressure supply.
5. A diaphragm for pressure regulators and other devices, comprising an annular member, flexible top and bottom members attached to the said annular member and forming with the same a closed chamber, a rigid support for the chamber on which said bottom member rests, and a flexible tube connected at one end to the said annular member, the other end of the tube being secured to a fixed support and adapted to connect with a source of pressure supply.
  6. A diaphragm for pressure regulators and other devices, comprising an annular member, flexible top and bottom members attached to the said annular member and forming with the same a closed chamber, a rigid support for the chamber on which said bottom member rests, and a tube formed into a coil encircling the said annular member, one end of the coil being secured to a fixed support and the other end being attached to the said annular member and opening into the chamber formed by the said annular member and the said flexible top and bottom members.

WILLIAM L. HAMILTON.
